FIG. 3

UNITED STATES PATENT OFFICE

VINCENT J. ZUANICH, OF OAKLAND, CALIFORNIA

CLAMP BLOCK

Application filed July 2, 1929. Serial No. 375,446.

This invention relates to improvements in clamp blocks and has for one of its principal objects the provision of a clamp block adapted for ready use by machinists and the like for supporting the heels of clamps or straps used on machine tools.

A further important object of this invention is to provide a clamp lock for ready use by machinists in factories, shops or the like whereby the work may be positively and securely supported in position and in a workmanlike manner.

Still another and further important object of this invention is the provision for the use in a machine shop or the like of a plurality of bench clamp blocks of various sizes and shapes whereby objects to be worked upon may be readily supported in desired position with the further idea of so distinguishing said bench blocks in appearance that they may be readily selected from scrap or work lying on benches or on the floor in the shop.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of a portion of a clamp or strap used on a machine tool illustrating the improved clamp block of this invention.

Figure 2 is a side elevation of the improved clamp block.

Figure 3 is a top view of the same.

Figure 4 is a vertical sectional view of one end of the block.

Figure 5 is a sectional view taken on the line 5-5 of Figure 2.

As shown in the drawings:

The reference numeral 10 indicates generally a portion of a machine table or the like upon which a piece of work 12 is supported and held in position by means of an ordinary clamp 14 and bolt 16.

In order that the clamp may be effectively adjusted with respect to the bolt and the work, a block comprising a portion of steel

tubing 18 is provided of substantially the same height as the work 12. Obviously, a number of these blocks are provided of various kinds so that any desired height may be selected.

Each block preferably includes a hard wood core 20 as best shown in Figures 4 and 5, the metal tubing 18 being shown square in cross section but which obviously may be round, triangular or any desired shape. The hard wood core is put in under pressure, and at each end of the block is provided a steel cap 22 maintained in position by means of a screw or the like 24. The cap protects the wood against damage and also aids in keeping the ends square. The wooden core will adequately withstand the greatest pressure produced by the bolt 16 and positively prevents buckling of the tube.

The blocks are preferably lacquered or painted in some bright color such as red or the like so as to be readily distinguished and selected. Openings 26 are provided in the sides of the blocks, the number of these openings varying with the dimensions of the block, and these are adapted to retain the lacquer so that the same cannot be readily worn off, the holes being further used for finger grips when the blocks are withdrawn from their containers.

The blocks may be made from two inches in length up to any desired size and steel shims may also be used with the blocks, these shims preferably ranging from one-sixteenth of an inch up to one inch in thickness so that the blocks and the clamp supports may be built up in progressive steps of one-sixteenth of an inch.

Heretofore, it has been the practice around machine shops to use blocks of wood or scrap pieces of metal on a clamp and screws and bolts have also been utilized in this connection, always with more or less unsatisfactory results.

It will be obvious that herein is provided a clamp lock which can be made in any desired size and shape and also in a variety of sizes and shapes so that any sort of work of practically any dimension may be adequately and positively clamped in position.

upon a machine table. This results in a more convenient series of operations so far as the work is concerned, and the fact that these blocks will not collapse, and are readily distinguished and selected is an extension to their use.

I am aware that many changes may be made and numerous details of construction varied throughout a wide range without departing from the principles of this invention, and I therefore do not purpose limiting the patent granted hereon otherwise than as necessitated by the prior art.

I claim as my invention:

15 A clamp block comprising a steel tube and a wooden filler and reinforcement in the tube comprising a unitary core extending throughout the length of the same, and forced into the tube under pressure, together with metallic caps on the ends of the tube and contacting the core and screws for maintaining said caps in position, said screws penetrating the material of the core, the edges of the ends of the tube being wedge-shaped, and corresponding angular grooves formed in the related outer edges of the said metallic caps, the tube having openings in its sides for finger grips.

In testimony whereof I affix my signature.

30 VINCENT J. ZUANICH.
